UNITED STATES PATENT OFFICE.

BENJAMIN WEXLER, OF BROOKLYN, NEW YORK, ASSIGNOR TO THE PEELE COMPANY, OF BROOKLYN, NEW YORK, A CORPORATION OF NEW YORK.

LOCKING MECHANISM FOR ELEVATOR DOORS.

Application filed October 31, 1913. Serial No. 260,484.

To all whom it may concern:

Be it known that I, BENJAMIN WEXLER, a citizen of the United States, residing at the borough of Brooklyn, in the city of New York, county of Kings, and State of New York, have invented certain new and useful Improvements in Locking Mechanisms for Elevator Doors, of which the following is a specification, reference being had therein to the accompanying drawings, which form a part thereof.

The invention relates to locking mechanisms for elevator doors, and more particularly to such a mechanism adapted for use in connection with oppositely sliding doors having movement in the same vertical plane, and of the counterbalanced, full automatic, or semi-automatic type.

In doors of the above character, it has heretofore been the practice to lock each door by means of an elongated latch lever mounted upon the structure supporting the rail upon which the lower door section has movement, said lever being adapted, when the door is closed, to pass under the hanger bar of this door section and thus by preventing the descent thereof, locking both door sections in the closed position. This lever is ordinarily brought to the inoperative position by a mechanism actuated by the engagement therewith of a shoe carried by the car, so as to prevent the opening of the door except when a car is at the opening closed by that door. Hence, before the lever can become operative to lock the door, it is essential that the car must leave the floor, or said shoe must be actuated so that, while the door is ordinarily closed before power is applied to the car, the latch mechanism does not become operative to lock the doors as a result of the closing movement of the door sections.

Elevator doors of this character possess considerable weight and with doors of the counterbalanced, or semi-automatic type, there is a likelihood of the connecting chains or cables to stretch slightly after a continued use of the door, thus creating a condition where there is a tendency of the doors to separate slightly, or of the lower door section, when the door is closed, not to come to the proper level, or meeting point of the sections, and thus cause the hanger bar thereof to be interposed in the path of movement of said lever in a manner to prevent

the lever passing beneath the bar and properly locking the door.

With full automatic doors there is a likelihood of the actuating cable to stretch slightly, with the same effect.

If a door is closed and not properly locked, the factor of safety afforded by the locking mechanism, which, as heretofore stated, is designed to prevent the opening of the door, except when a car is at the door opening closed thereby, is absent, since the door may be opened from the floor side of the opening.

To avoid this condition, I provide a locking mechanism so constructed that it will be automatically actuated by a car in a manner to permit the opening of the door only when a car is at the door opening closed thereby, and will engage the hanger bar of the lower door section to positively lock the door in the closed position either when the lower section is at the proper meeting point of the two door sections, or when it sags or drops slightly below this position as the result of stretch in the cable connecting the door sections, or in the actuating cable in a full automatic door, or because of a slight rebound of the door sections, or as a result of the operator failing to bring the sections properly together.

The invention consists primarily in a locking mechanism for elevator doors, consisting of the combination with a plurality of door sections movable in opposite directions, and a flexible connection between said sections, the lower of which sections has a laterally projecting hanger bar thereon, of an oscillatory lever pivoted adjacent the side of the door, said lever having a plurality of stop surfaces thereon adapted to alternatively pass beneath said hanger bar, means having a normal tendency to thrust said lever towards said hanger bar, and cooperating means operative upon said lever, and carried by an elevator car, whereby said lever is withdrawn from its operative relation to said hanger bar, or permitted to assume its operative relation thereto; and in such other novel features of construction and combination of parts, as are hereinafter set forth and described, and more particularly pointed out in the claims hereto appended.

Referring to the drawings,
Fig. 1 is a view of an elevator door em-

bodying a locking mechanism made in accordance with my invention, said view being from the shaft side;

Fig. 2 is a side view of the locking mechanism, shown in the locked position, where the door sections meet upon the proper parting line, a fragmentary portion of an elevator car being shown out of the operative relation to said mechanism; and

Fig. 3 is a view similar to Fig. 2, with the elevator car in the operative position with relation to the locking mechanism, indicating in dotted lines the operation of the locking mechanism in the event that the doors do not meet on the proper level.

Like letters refer to like parts throughout the several views.

In the embodiment of my invention shown in the accompanying drawings, I have illustrated in Figs. 1 and 2 a single elevator door structure of the counterbalanced type, showing a locking mechanism made in accordance with my invention, applied thereto. In Fig. 3 I have shown a structure of a locking mechanism embodying my invention adapted for use in connection with semi-automatic, or full automatic doors.

The terms counterbalanced, semi-automatic, and full automatic, means, respectively, doors wherein opposed sections are connected so as to counterbalance each other; doors wherein one of said sections is overweighted with relation to the other, so that the door will either be self-opening, or self-closing, but must be manually operated as to the other movement; or doors similar to the semi-automatic type wherein means are provided to relieve the operator of the necessity of either manually opening or closing the doors.

In the accompanying drawings, I have indicated a door composed of two sections, *a* and *b*, vertically slidable in opposite directions in the same plane. Said doors are mounted upon vertical tracks, or guides, *c*, upon opposite sides of the door opening, and are connected by flexible chains or cables *d* passing over suitably arranged pulleys *e*.

The lower door section *b* is provided with a laterally extending hanger bar *f*, projecting beyond the guides or tracks *c*, which hanger bar provides the proper offset connection for the chain or cable *d*.

When the door is opened, the section *b* in its entirety passes the sill of the door, and the section *a* passes above the lintel thereof, the proper meeting point of the doors being midway between said sill and lintel.

For locking the doors in the closed position, I provide a latch lever *g* pivotally mounted upon the angle bar *h*, supporting the track or guide *c*, adjacent the side of the door.

Said lever *g* is normally thrust in the path of the hanger bar *f*, means operative upon

said lever and co-operating means carried by an elevator car being provided, whereby said lever will be automatically removed from this position when a car is adjacent the door opening, so as to permit the opening 70 of the door.

In the form of the invention shown in the drawings, this means comprises a short secondary lever *i* also pivoted upon the bar *f*, one arm of said lever being pivotally connected with an arm of the lever *g* and the other arm thereof having adjustably mounted thereon an impact member *j* adapted to be engaged by a shoe *k* carried by the elevator car *m*. Acting upon the lever *i* is a spring *n*, which spring is so set as to have a normal tendency to thrust the impact member *j* into the path of the shoe *k* with a resultant oscillation of the lever *g* in a manner to bring it within the path of movement of the hanger bar *f*.

The length of the upper arm of the lever *g* is such as to bring the stop surface *o*, formed by the top of this lever, below the lower edge of the hanger bar *f*, said lever being provided with a projection *o'* having a bevelled lower face adjacent the top thereof, and presented toward the path of movement of the hanger bar *f*, forming a second stop surface a short distance below said bar, when 90 it is in this position. The distance between the stop surfaces *o* and *o'* need not be great, it being merely necessary to afford a sufficient distance to compensate for a resonable stretch or elongation of the cable or chain 100 *d*, or of the actuating cables of semi-automatic, or full automatic doors.

In the form of the invention shown in Fig. 3, the construction is as heretofore described, with the exception that I provide a supplement latch member *p* adapted to engage the top of the hanger bar *f* when the door is opened, a construction which is particularly adapted for self-closing, semi-automatic doors.

The locking mechanism heretofore described is duplicated upon opposite sides of each door, in order to provide a suitable support for the section *b*, while it is closed, and minimize any tendency of the door to sag on one side.

The use of a locking mechanism, such as I have described, does not in any way interfere with the fireproof character of the door, since the astragal is of sufficient depth to span any gap which will result because of the distance between the locking point afforded by the surface *o* and that afforded by the surface *o'*. At *g* I have shown the adjustable stops ordinarily used in doors of the truckable type.

The operation of the herein described mechanism is substantially as follows.

When a door is properly set, and the chains or cables *d* are of the proper length, 100

the two door sections will meet and the hanger bar *f* will be so positioned that the stop surface *o* will pass thereunder. When it is desired to open a door, it is essential that the car *m* be stopped adjacent the door opening, to bring the shoe *k* in operative relation with the impact member *j* carried by the lever *i*. The construction of the shoe of said impact member is such, that, as it comes into operative relation to the impact member *j*, it will rock the lever *i* against the tension of the spring *n*, and by reason of the pivotal connection between said lever *i* and the lever *g*, rock said last named lever in a manner to bring the stop surfaces *o* and *o'* thereof, without the path of movement of the hanger bar *f*, and thus permit the door to either open automatically, or be opened manually.

While a car is at the door opening, the door may be opened or closed, but the latch mechanism does not become operative until the lever *i* is released as a result of a movement of the shoe *k*. When the lever *i* is released, the spring *n* will oscillate the lever *i*, and through it, the lever *g*, in a manner to bring the stop surface *o* or *o'* within the plane of movement of the hanger bar *f*. If the sections *a* and *b*, when closing a door, meet at the proper point, the surface *o* will pass beneath said hanger bar, but, to the contrary, if, through the failure of the operator to properly close the door, or of the doors to properly meet by reason of the elongation of the chains or cables *d*, the end of the lever *g*, adjacent the surface *o*, will engage the face of the hanger bar *f* and the surface *o'* alone will be brought within the plane of movement of said bar, thus ensuring the locking of the door, notwithstanding that the two sections thereof are not properly positioned with relation to each other.

It is to be observed that normally the closing movement of the lower door section does not contribute in any way, towards the operation of the locking mechanism, so that even though a door may be closed before a car is started, or even though the operator may actually bring the doors together, this does not ensure the locking of the doors, which must normally occur as a result of some movement, independently of that of the door sections themselves.

While, in the accompanying drawings, I have shown a latch lever having but two stop surfaces thereon, it is apparent that this number may be increased, if desired, providing that the door structure affords ample space for the desired increase in the width of the lever *g*.

In Figs. 1 and 2 of the drawings, I have shown the locking mechanism in connection with door sections so set as to permit the surface *o* to pass beneath the hanger bar *f*, and in Fig. 3, I have indicated in dotted lines, the relation of parts in the event that

the condition of the door is such as not to permit said surface *o* to pass beneath the hanger bar *f*, this view showing said hanger bar in engagement with the surface *o'*.

I have shown and described a well known structure of actuating shoe *k*, it being understood, however, that any desired construction of shoe for actuating the lever *i* may be employed.

In the event that the car *m*, after a door has been opened, should creep so as to bring the shoe out of the operative range of the impact member *j*, the bevelled undersurface of the shoulder, forming the bearing surface *o'*, will, with the engagement of the upwardly moving hanger bar, result in a camming action forcing the lever *g* backwards in a manner to permit the closing of the door.

It is not my intention to limit the invention to the precise details of construction shown in the accompanying drawings, it being apparent that such may be varied without departing from the spirit and scope of the invention.

Having described the invention, what I claim as new, and desire to have protected by Letters Patent, is:—

1. A locking mechanism for elevator doors, consisting of the combination with a plurality of door sections movable in opposite directions, the lower of which sections has a laterally extending hanger bar thereon, and a flexible connection between said sections, of an oscillatory lever pivoted adjacent the side of the door, said lever having a plurality of stop surfaces thereon arranged upon different horizontal planes and adapted to alternatively pass beneath said hanger bar, the upper of said surfaces being adapted to engage said hanger bar when the doors are completely closed, and the lower of said surfaces being adapted to permit a limited opening movement of the door before engagement with said hanger bar, means having a normal tendency to thrust said lever toward said hanger bar, and co-operating means operative upon said lever and carried by an elevator car, whereby said lever may be withdrawn from its operative relation to said hanger bar, or permitted to assume its operative relation thereto.

2. A locking mechanism for elevator doors, consisting of the combination with a plurality of door sections movable in opposite directions, the lower of which sections has a laterally extending hanger bar thereon, and a flexible connection between said sections, of an oscillatory lever pivoted adjacent the side of the door, said lever having a shoulder adjacent the top thereof, forming a stop surface parallel with the surface formed by the top of said lever and projecting toward said hanger bar, said

top and stop surfaces being adapted to alternatively pass beneath said hanger bar, the upper of said surfaces being adapted to engage said hanger bar when the doors are 5 completely closed, and the lower of said surfaces being adapted to permit a limited opening movement of the door before engagement with said hanger bar, means having a normal tendency to thrust said lever toward 10 said hanger bar, and co-operating means operative upon said lever and carried by an elevator car, whereby said lever may be withdrawn from its operative relation to said hanger bar, or permitted to assume its 15 operative relation thereto.

3. A locking mechanism for elevator doors, consisting of the combination with a plurality of door sections movable in opposite directions, the lower of which sections 20 has a laterally extending hanger bar thereon, and a flexible connection between said sections, of an oscillatory lever pivoted adjacent the side of the door, said lever having a plurality of stop surfaces thereon arranged upon different horizontal planes and 25 adapted to alternatively pass beneath said hanger bar, the upper of said surfaces being adapted to engage said hanger bar when the doors are completely closed, and the lower 30 of said surfaces being adapted to permit a limited opening movement of the door before engagement with said hanger bar, a secondary lever mounted adjacent the sill of a door opening and pivotally connected with said first named lever, 35 an impact member carried thereby, means carried by an elevator car adapted to operatively engage said impact member, and a spring acting on said secondary lever, whereby said first named lever is normally projected towards said hanger bar, and said 40 impact member is normally projected into the operative relation to said means.

and said impact member is normally projected into the operative relation to said means.

4. A locking mechanism for elevator doors, consisting of the combination with a plurality of door sections movable in opposite directions, the lower of which sections 45 has a laterally extending hanger bar thereon, and a flexible connection between said sections, of an oscillatory lever pivoted adjacent the side of the door, said lever having a shoulder adjacent the top thereof, forming a stop surface parallel with the surface formed by the top of said lever and projecting toward said hanger bar, said stop surfaces being adapted to alternatively pass 50 between said hanger bar, the upper of said surfaces being adapted to engage said hanger bar when the doors are completely closed, and the lower of said surfaces being adapted to permit a limited opening movement of the door before engagement with said hanger bar, a secondary lever mounted adjacent the sill of a door opening and pivotally connected with said first named lever, 55 an impact member carried thereby, means carried by an elevator car adapted to operatively engage said impact member, and a spring acting on said secondary lever, whereby said first named lever is normally projected towards said hanger bar, and said impact member is normally projected into the operative relation to said means.

In witness whereof, I have hereunto affixed my signature, this 21st day of October, 1918, in the presence of two subscribing witnesses.

BENJAMIN WEXLER.
